UNITED STATES PATENT OFFICE.

ALBERT H. EMERY, OF NEW YORK, N. Y., ASSIGNOR TO THE EMERY SCALE COMPANY, OF STAMFORD, CONNECTICUT.

DYNAMOMETER.

SPECIFICATION forming part of Letters Patent No. 278,912, dated June 5, 1883.

Application filed February 5, 1881. (No model.)

To all whom it may concern:

Be it known that I, ALBERT H. EMERY, of the city, county, and State of New York, have invented certain new and useful Improvements 5 in Dynamometers, of which the following is a specification.

This instrument is constructed with a suspension stem and beam connected by rods extending down through a case of cylindrical or 10 other form to a load-beam. The load is applied preferably to a stem swiveled in a pair of cross-heads, between which is interposed a buffer-spring. Said cross-heads are connected to the case by fixing-studs. The load is trans- 15 mitted from the case to a pressure-column on the load-beam of the suspension-yoke through the medium of the fulcrum attachments of a load-lever connected by one or more secondary levers with a resisting-spring to take up the 20 pressure and a rotary indicator to show the extent and value of the deflection of the levers produced by the load. The double levers transmit the pressure centrally of the case, so as to entirely obviate any lateral strain. The base 25 of the column upon which the pressure of the load-levers is sustained is connected to the load-beam, and is preferably flanged to form a stop-plate to limit the movement of the parts by contact with a part of the case. The sus- 30 pension and load beams are stayed against motion transversely to the load strain by means of flexible annular fixing-plates applied at the extremities of the case. The intermediate lever of the system connects by a flexible trans- 35 mitting-plate with the heel or fulcrum-block of the final lever, said fulcrum-block being connected to the case by vertical and horizontal flexible plates, which respectively suspend it and stay it against horizontal motion. Motion 40 is transmitted from the free end of the final lever to a rotary indicator by means of a band attached at one end to the extremity of the lever, and at the other end coiled on a drum on the indicator-shaft.

45 In the accompanying drawings the invention is represented by three views, numbered 129 to 131, inclusive. Figure 129 is a front elevation of the instrument. Fig. 130 is a vertical section thereof. Fig. 131 is a view of the 50 lower end on a smaller scale.

The following parts are substantially similar

in construction and operation to parts indicated by corresponding numbers in another application of even date with this, which describes their application to a dynamometer of 55 greater capacity, constructed with liquid-pressure chambers, the suspension-stem 901, suspension-beam 902, case 903, fixing-plates 904 and 909, suspending-rods 905, lock-nuts 906, load-beam 907, clamp-nuts 908, casing-ring 910, nut 60 916, washer 917, pin 918, screw 920, packing-rings 926, upper part of pressure-column 928, screws 929, fastening fulcrum-block 930, transmitting-plate 932, load-lever 933, fulcrum-plate 934, clamp plate and screw 935, transmitting-plate 936, clamping plate and screw 937 938, thin plates 939 939^a, clamping plates 940, clamp-connections 941 941^a, load-lever 942, fixing and resisting spring 943, clamping plates and screws 944, clamp 945, temperature-spring 70 946, clamp plates 947, temperature and adjusting rod 948, transmitting-plate 949, clamp 950, fulcrum-block 951, clamp 952, transmitting-lever 953, screws 954 954^a, fulcrum-plate 955, bracket 956, plate and screw 957, screw 75 958, flexible fixing-plate 959, clamp-plates 960 961 963, band 962, drum 964, indicator-shaft 965, indicator 966, brackets 967 968, hair-spring 969, pin 969^a, dial 970, door-frame 971, glass 972, stop-studs 976 977. 80

The suspension-stem 901 is secured by lock-nuts 906 to the suspension-beam 902, in which are fixed suspending and connecting rods 905. These rods are formed with shoulders, against which is rigidly clamped, by means of nuts 85 908, the load-beam 907. The base 979 of the pressure-column is fixed to the load-beam 907 by a screw, 920, and is flanged, as shown, constituting a stop-plate to limit, by contact with the casing-ring 910, the upward movement of 90 the case relatively to the suspension-yoke when relieved of a load. The suspending-beam 902 is fixed against lateral motion by the flexible annular plate 904. The load-beam 907 is fixed to the case 903 and ring 910 and secured against lateral motion by the flexible annular plate 909. These fixing-plates 904 and 909 may be secured at their edges, as shown in Fig. 130, and more specifically described in other applications. The load-stem 984 is preferably swiveled within a moving cross-head, 980, being supported thereon by a nut, 916, 95 100

and washer, 917, locked together by a pin, 918. The moving cross-head 980 rests on a spring, 981, of rubber or other material, bearing on the load cross-head 983, which is rigidly connected by nuts 985 and fixing-studs 982 to the case 903. Instead of the compression-spring 981, a tension-spring of any suitable material may be placed below the cross-head 983, and in this case the moving cross-head 980 may be dispensed with. The load which is thus applied to the case 903 is transmitted to the pressure-column 928 979 and load-beam 907 through the medium of the fulerum-bracket 930, flexible fulerum-plate 934, and the fulerum-block of a double or skeleton lever, 933, 15 constituting the primary load-lever, and connected by the flexible thrust-plate 932 and clamp 931 to the upper part, 928, of the pressure-column. The double or skeleton load-lever 933 consists of two parallel bars connected at their extremities, and may be made in one piece, as shown in Fig. 130. It is connected by the flexible plate 934 and clamp plate and screw 935 to the fulerum-bracket 20 930, the latter being secured by screws 929 to the case 903. From the primary load-lever 933 pressure is transmitted through a flexible plate, 936, (held by clamps 937 938,) to a second double or skeleton lever, 942, fulerumed 25 by a compound flexible joint constituted of thin plates 939 939^a and clamps 940. A clamp, 941, fixes the plate 939 to the transmitting-lever 942, and a clamp, 941^a, fixes the plate 939^a to the case or to a suitable bracket attached thereto. 30 One or more flexible plates, 943, fastened by an adjustable clamp or clamps, 944, to the fulerum-bracket 930, and by a clamp or clamps, 945, to the lever 942, constitute springs to resist the deflection of the levers under pressure 35 of a load and also to stay the lever 942 against horizontal movement.

946 represents a temperature-spring, fastened to the back part of the lever 942 by a clamp-plate, 947, and to the case by a temperature and adjusting rod, 948, which is formed wholly or in part of metal more or less expansible than that of the case, in order to counteract automatically the effect of changes in temperature, as may be necessary. The rod 948 is 40 screwed within the case, as shown in dotted lines, Fig. 129, so that it may be set up or down to vary the pressure of the spring on the lever and to set the rotary indicator. A flexible transmitting-plate, 949, is fastened by a clamp, 950, to the free end of the transmitting-lever 942, and by a clamp, 952, to the fulerum-block 951 of a transmitting-lever, 953, which is fixed to the said fulerum-block by screws 954. The fulerum-block 951 is suspended by 45 a flexible plate, 955, to a bracket, 956, attached to a lug, 986, on the case 903, and forming also the attachment for the flexible fixing plate or plates 959, by which the said fulerum-block is secured against horizontal motion. The fulerum-plate 955 is clamped to the fulerum-block 951 by screws 954 954^a, and to the bracket 956 by clamp 957. The horizontal fixing plate or

plates 959 are attached to the fulerum-block 951 by clamp 960, and to the bracket 956 by clamp 961. The use of the bracket is beneficial in enabling the attaching of the flexible plates to the said bracket and to the fulerum-block before inserting the whole in the case, after which the setting and securing of the bracket are readily effected. The fixing-spring 959 may be attached directly to a lug on the case 903, if preferred. The fulerum-block or heel-piece 951 is so constructed that the free part of the fulerum plate or plates 949, or the part exposed to flexure, reaches above the lower 50 flexible part of the fulerum plate or plates 955. This construction tends to increase the fulerum distance between the plates 949 and 955 as the lever 953 rises. This tends to hasten the rotation of the indicator, which is retarded by 55 other increasing resistances. To the free end of the lever 953 is secured adjustably by a clamp, 963, one end of a metallic band, 962, the other extremity of which is coiled on a drum, 964, on the shaft 965 of the indicator 60 966. To the shaft is also fixed one end of a hair-spring, 969, coiled in the opposite direction from the band 962, and attached at its other end to a pin, 969^a, fixed in the load-lever 942. The hair-spring works in opposition to 65 the band 962, so as to restore the indicator to zero and keep the parts taut. The double or skeleton levers enable the use of transmitting-plates made wide for strength and thin for flexibility. By applying the strains centrally 70 within said skeleton levers, lateral or oblique strains are avoided and the accuracy and durability of the instrument are greatly enhanced.

Whatever novel subject-matter I have set forth and not claimed or attempted to claim 75 herein I have claimed or attempted to claim in other applications or have reserved to be claimed in future original applications.

The following is here claimed as new:

1. The combination of the beam 902, connecting-rods 905, and double balancing-levers 933 and 942, substantially as and for the purposes set forth.

2. The combination of the load-beam 907, connecting-rods 905, beam 902, one or more 115 load-levers, 933 942, and case 903, substantially as and for the purposes set forth.

3. The combination of the load-beam 907, column-base 979, pressure-column 928, transmitting-plate 932, and load-lever 933.

4. The combination of the load-beam 907, screw 920, pressure-column 928, and the pressure-column base 979, constructed to operate as a stop-plate in the manner described.

5. The combination of the pressure-column 125 928, pressure-column base 979, screw 920, load-beam 907, flexible fixing-plate 909, casting-ring 910, and case 903, as set forth.

6. The combination of the case 903, fixing-studs 982, load cross-head 983, spring 981, and moving cross-head 980 with a suitable load attachment.

7. The combination of the suspending-beam 902, connecting-rods 905, load-beam 907, cas-

ing-ring 910, case 903, fixing-studs 982, load cross-head 983, and spring or springs 981 with a suitable load attachment.

8. A spring interposed between the load attachment and the load cross-head 983, to relieve the instrument of shock and transmit the pressure of the load to the weighing apparatus.

9. The combination of the attaching-bracket 956 and lug 986 with the flexible plates 955

and 959, and with the fulerum-block 951 of the lever 953.

10. The combination of the flexible fixing-plate 959, fulerum-block 951, transmitting-lever 953, band 962, drum 964, and indicator-shaft 965.
